(57) **CLAIM**

The ornamental design for a pinch-off pliers, as shown and described.

DESCRIPTION

FIG. 1 is a perspective view of the pinch-off pliers;
 FIG. 2 is another perspective view thereof;
 FIG. 3 is a right side elevation view thereof;
 FIG. 4 is a left side elevation view thereof;
 FIG. 5 is a top plan view thereof;
 FIG. 6 is a bottom plan view thereof;
 FIG. 7 is a front elevation view thereof; and,
 FIG. 8 is a rear elevation view thereof.
 All broken lines illustrate portions of the pinch-off pliers that form no part of the claimed design.

1 Claim, 2 Drawing Sheets(56)
